Inventor
I. A. Viersen

by Davis & Hayes Atty's.

UNITED STATES PATENT OFFICE.

IPE A. VIERSEN, OF OKMULGEE, OKLAHOMA.

DESIGN FOR AN AUTOMOBILE SIGNAL.

Application filed January 10, 1928. Serial No. 24,795. Term of patent 14 years.

To all whom it may concern:

Be it known that I, IPE A. VIERSEN, a citizen of the United States, and a resident of Okmulgee, in the county of Okmulgee, State of Oklahoma, have invented a certain new, original, and ornamental Design for an Automobile Signal, of which the following is a specification, reference being had to the accompanying drawing, forming part thereof.

Figure 1 of the drawing shows a front elevation of an automobile signal embodying my improved design; and

Figure 2 is a side elevation of the same.

I claim:

The ornamental design for an automobile signal as shown.

IPE A. VIERSEN.
